UNITED STATES PATENT OFFICE.

GEORGE W. WILLIAMSON, OF PETALUMA, CALIFORNIA.

ADVERTISING-KIOSK.

1,240,637.

Specification of Letters Patent. Patented Sept. 18, 1917.

Application filed February 24, 1917. Serial No. 150,753.

To all whom it may concern:

Be it known that I, GEORGE W. WILLIAMSON, citizen of the United States, residing at Petaluma, in the county of Sonoma and 5 State of California, have invented new and useful Improvements in Advertising-Kiosks, of which the following is a specification.

This invention relates to sign exhibiting, and more especially to electrically controlled 10 changeable exhibitors; and the object of the same is to produce a slowly revolving kiosk or similar structure adapted to be set up in halls, on the street, or in public places, and provided on its several faces with movable 15 tapes or webs intermittently actuated to display pictures, signs, or advertising matter and the like through window openings in the walls of the revolving kiosk, so that persons on all sides of the latter may see the 20 same. The device is operated electrically by power taken from the wires of a direct or alternating current system, and by preference we make use of the same motor or motors for revolving the kiosk constantly and 25 moving the webs intermittently, and employ buttons or other circuit closers on the webs themselves to actuate clutch mechanism for starting and stopping the movement of the rollers which carry the webs and for reversing them in their direction of movement 30 when the end of the webs has been reached.

Details will be found in the following specification, reference being had to the accompanying drawings wherein—

35 Figure 1 is an elevation of this kiosk.

Fig. 2 is a diagram giving a plan view of the wiring from the hub of the kiosk to the motor, and showing terminals on certain of the spokes of the kiosk which move over 40 circuit closer blocks on the fixed base thereof to close certain circuits as herein described; and

Fig. 3 is an elevation of the power shaft driven by said motor and a diagrammatic 45 view of the mechanism by which it is connected with the rollers of one web-actuator; giving a continuation of the circuits of Fig. 2 and the magnets and devices controlled thereby.

50 Fig. 4 is a detail view of a piece of one web or tape near its end, showing the series of buttons for causing its intermittent movement and one of the main buttons for causing a reversal of the direction of its movement.

Fig. 5 is a detail showing the connection between the power shaft and the base of the kiosk whereby the latter is rotated with the motor.

Fig. 6 is an enlarged elevation, partly in 60 section, showing all the mechanism for controlling the action of the roller at one end of one of the webs.

Fig. 7 is a large view of the kiosk partly 65 in section, giving an elevation of the main shaft and the mechanism which it drives, and a detailed sectional view of the collector rings whereby current is taken from the wires of a direct circuit or alternating circuit and delivered to the motor.

Fig. 8 is a sectional detail of one of the 70 collector rings and its brush taken on about the line 8—8 of Fig. 7.

Fig. 9 is a detail of the worm mechanism.

In Fig. 1 I have shown a kiosk K in elevation, the same being the revolving structure which carries the advertisement. Mounted 75 on a base 1 which is fast upon the floor or rises above the same is the revolving structure, herein shown as a kiosk which comprises 80 an upright wall 2 made in panels as shown, and each panel provided with two framed openings 3 disposed preferably one above the other, the whole being surmounted by a roof 4 suitably ornamented in about the 85 manner illustrated or after any design which is practical and serviceable. There may be as many side faces or panels as desired, as eight or sixteen, and each panel could have two openings one above the other or a 90 greater or less number as preferred. It is my intention that the entire structure shall revolve slowly on an upright axis, and that tapes or webs 5 mounted on upper and lower rollers 6 and 7 shall move intermittently 95 across the openings 3, each block or space (see Fig. 4) carrying one picture or advertisement and the same being changed at intervals of perhaps every thirty seconds or once for each revolution of the kiosk. In 100 other words, at one point in the revolution the picture or advertisement changes rather quickly, then the kiosk rotates or revolves on its axis rather slowly so that persons on all sides of the same within the apartment in 105 which the structure is situated may see the picture or read the advertisement, and at the conclusion of the revolution the picture or advertisement again changes quickly; and after the web has run its course and reaches 110

either extreme, its direction of movement is automatically reversed by mechanism which will be explained below.

At a suitable point within the kiosk is an electric motor 10 whose shaft is connected by gearing or otherwise at 11 with an upright power shaft 12 journaled in bearings in the kiosk in a manner not necessary to illustrate. I may say at this point that there could be one of these power shafts for each pair of upright openings 3, each shaft driven by its own motor, or the several power shafts could be properly connected with each other by gearing not shown and driven by a single motor. I consider this detail unimportant, and in the present case have illustrated but a single motor and a single shaft, as that is all that is necessary for the purposes of description. The lower end of the power shaft 20 may carry a gear meshing with a ring of gear teeth 13 on the fixed base, so that the rotation of the power shaft causes the revolution of the kiosk; although of course it would be possible to impart revolution there- 25 to by a separate motor. At proper points, the shaft 12 carries worms 14 and 15 pitched in opposite directions, the former engaged with an upper worm gear 16 and the latter with a lower worm gear at 17 as best seen in Fig. 3, and the hubs 18 of these gears are slidably keyed as at 19 on their respective shafts 20 as seen in Fig. 9. The upper shaft carries a friction disk 26 contacting with the enlarged head of the roller 6, and the lower shaft carries a similar disk 27 contacting with the head of the lower roller 7; and it will be clear from the opposite pitch of the worms 14 and 15 that the friction gearing between the upper shaft and upper 30 roller will drive it in one direction so as to draw the web 5 upward, whereas the friction gearing between the lower shaft and the lower roller will move the web in the opposite direction so as to draw it downward—hence mechanism is necessary to project one shaft at the time the other is retracted. In Fig. 3 the upper shaft is shown as projected by its spring 28, whereas the spring 29 of the lower shaft is under compression and the shaft is retracted so that its disk 27 does not touch the head of the roller 7. Each of these springs may be coiled around the shaft between the disk and the hub of the worm gear as shown. 35 The rollers have brakes 6' and 7'. The gear shifting mechanism is actuated electrically by magnets within a battery circuit which is opened and closed intermittently by the revolution of the kiosk, as I will now describe. The numeral 30 designates a retracting magnet or solenoid acting directly on the rear end of the shaft 20, and the latter has a notch 31 which is engaged by the tip of a spring-pressed catch 32 thrown normally upward as shown, but re-

tracted by a trip magnet 33. The disposition of parts is such that when the shaft is retracted by the magnet 30 the notch comes over the tip of the catch and the latter moves into the same to hold the shaft retracted until trip magnet 33 is energized to trip the catch at a time when there is no current within the retracting magnet 30. From a battery 34 leads a wire 35, through a switch yet to be described and numbered and along one branch 36 to the upper magnet, thence along a wire 37 to a circuit-closer 38, shown in Fig. 3 as consisting of two rollers bearing on opposite sides of the web 5, and normally out of contact, and from this circuit 40 closer back to the battery 34; and between the rollers at intervals pass buttons 39 arranged in a series along one edge of the web 5 as seen in Fig. 4 and spaced from each other a distance equal to the height of one picture or one display advertisement. Beyond said switch the other branch wire 36' leads to the lower retracting magnet, and thence by wire 37' to said circuit closer and back to the battery along the course already outlined, and therefore when the circuit is closed by the passage of a button an impulse will be directed to and through one magnet according as the switch is set, with the result that either the upper or lower shaft 45 will be retracted and the movement of the web in a corresponding direction interrupted. From said branch 36 another wire 40 leads to a terminal 41 standing adjacent another terminal 42, said terminals being 50 carried by the kiosk mechanism as indicated in Fig. 2, and therefore revolving with it. At one or more points on the base beneath this mechanism is a circuit closing device such as a block 43, and at each revolution of the kiosk these terminals move across said block and are thrown into communication with each other. This would be the case if it were desired that the picture or advertisement be changed once at each revolution of the kiosk; if it should be the desire to have it changed oftener a larger number of blocks may be employed. From the second terminal 42 a wire 44 leads to the upper trip magnet 33, and thence by wire 45 back 55 to the battery. From the other branch wire 36' leads a second wire 40' through the lower trip magnet 33 and another pair of terminals 41' and 42', carried at another point within the kiosk, thence back by wire 60 44' past the upper trip magnet 33, and along a wire 45 to the battery. It will be observed that these circuits for the trip magnets are respectively controlled by circuit closers disposed at different points within the revolving structure or kiosk, but, like the retracting magnets, their actuation is dependent upon the setting of said switch. It will also be observed that the wiring is such as to permit the catch 32 of either trip magnet to 65

rise and engage the notch 31 in the shaft 20, just at a time when the latter is retracted by its magnet 30 in a manner more fully set forth below. Finally it will be observed 5 that the interrupting mechanism is actuated intermittently according to the spacing of the buttons 39 in the series along one edge of the web, whether the latter is moving upward or downward, and if each picture or 10 advertisement is twenty-four inches in height, the buttons in said series will be spaced that distance for a purpose which will be clear.

The reversing mechanism for changing 15 the direction of movement of the web after it has reached one end or the other, will now be described: The switch above mentioned I have numbered 50, and the wire 35 is shown in Fig. 2 as led to its pivot 51, 20 while one arm moves from the point 56 connected with the branch wire 36 to the point 56' connected with the branch wire 36'. The other arm projects forward and stands in position to be struck by a button 59 carried 25 by the web 5, and disposed adjacent the opposite edge of the same to the buttons 39 as seen in Fig. 4; and of these buttons 59 there are but two, one placed near each end of the web. When now the web has been 30 unreeled from the lower roller 7 and moved upward as indicated in the arrow in Fig. 3 until it approaches its lower extremity and is mostly wound on its upper roller 6, the button 59 strikes the tip of the switch-lever 35 50 and moves it from the full lined position in that view to the dotted line position, and the result is that the wire 35 is switched from contact at 56 with the branch 36, into contact at 56' with the branch 36'. There- 40 after the interrupting impulses produced by the passage of the buttons 39 between the rollers of the circuit closer 38, will be diverted to the lower retracting magnet 30 and trip magnet 33 to cause the web 5 to 45 move downward, while the upper friction gear 26 is out of action because the upper shaft 20 stands retracted and latched in that position. The web will then move downward step by step at intervals as con- 50 trolled by the circuit closer within the kiosk until it is nearly all wound on the lower roller 7, when the uppermost button 59 will again change the position of the switch 50, whereupon the web will resume its upward 55 movement, step by step.

Thus it will be observed that I have provided mechanism controlled electrically by circuits taken from a single source of energy, for interrupting the movement of the web 60 either upward or downward at intervals corresponding with the complete revolution of the kiosk if but a single block 43 be used, or oftener if more blocks are used, and for reversing the direction of movement of the 65 web when it approaches either its upper or

lower extremity. I have described the mechanism with respect to but one web, although of course it will be duplicated for the others, and as above suggested there may be but a single motor geared to the upright shafts or 70 there may be independent motors for the various shafts. Also the kiosk may be rotated by this motor or by a separate motor. I would have it revolve rather slowly, whereas the shifting of the pictures or advertisements should occur rather quickly, and preferably at only one point within the revolution of the kiosk. Provision may be made for throwing light on the face of each picture or advertisement, or for illuminating 75 the interior of the kiosk so that the light may shine through the webbing, which in that case would be transparent.

Anticipating the fact that this machine may be located at times where a direct current is available and at other times where the current is an alternating one, I have made provision for utilizing a current of either kind and connecting it with the motors. Reference is now made to Figs. 7 and 80 8, and in the former I have also shown some details of construction of the interior of the kiosk, although these are not essential. From the floor or base 1 rises a fixed hollow pillar 60 whose head 61 is surrounded by four grooves 62, and each groove contains a ring 63. The feed wires D, C for the direct current, and A, B for the alternating current are led up through the pillar and branched within the head, two of them being connected with the two uppermost rings 63 and the other two with the lowermost rings in any suitable manner. Fixed on the base around said pillar is a member 64 which may well carry the gear ring or teeth 90 13 referred to above, and 13' is the gear at the lower end of the main shaft 12 engaging these teeth. Said member may well form the lower element of a ball bearing, the upper element being the hub 65 of the 95 kiosk which surrounds the pillar, and said hub carries arms 66 which support the inclosing wall 2, the latter carrying the roof 4, as first described above. Said hub also carries a block 67 in which are located two 100 pairs of brushes 68 thrown normally inward by springs 69 into contact with the rings 63, and wires (not shown) are led from each pair of blocks to the motor or motors in a manner which will be clear. In Fig. 2 I 105 have shown wires marked D, C led from binding post which diagrammatically indicates one pair of blocks, to the motor 10; whereas the binding posts marked A, B 110 which would be connected with the brushes 115 contacting with the rings of the alternating current, are here cut out. Therefore in this illustration the motor is driven by wiring from the direct current. From this description it will be obvious that whatever 120 125 130

the nature of the current supplied and whatever the windings of the various motors (so long as they are all alike) proper connections may be made from the source of energy 5 to drive the machine without changing the construction of parts or the wiring excepting that the proper pair of brushes must be connected up with the motor.

What is claimed as new is:—

- 10 1. In a changeable exhibitor, the combination with a web-actuating roller, a longitudinally movable driving shaft therefor having a notch, and a friction disk on the shaft adapted to contact with the head of the roller; of a solenoid in which the rear end of the driving shaft is mounted, an electrically controlled catch adapted to engage said notch when the driving shaft is retracted and its friction disk out of contact with the roller-head, and means for alternately actuating the solenoid and the catch.
- 15 2. In an exhibitor of the class described, the combination with upper and lower rollers, a web wound thereon and having display panels, and a series of buttons along one edge of the web corresponding in number with the panels; of a power shaft, driving shafts having disks contacting with said 20 rollers for rotating them respectively in opposite directions, electrically controlled means for moving either of said driving shafts to throw its disk out of action while the other remains in action, thereby to wind 25 the web in either direction, electrically controlled means for throwing the active disk

out of action intermittently, a circuit breaker whose terminals stand in the path of said buttons, and a power circuit through said circuit-breaker and the last named means, 40 for the purpose set forth.

3. In a changeable exhibitor, the combination with a web-actuating roller, a driving shaft therefor having a friction disk adapted to contact with the head of the 45 roller and a notch, a worm wheel on said shaft, a power shaft having a worm engaging said wheel, a solenoid in which the rear end of the driving shaft is mounted, an electrically controlled catch adapted to engage 50 said notch when the driving shaft is retracted and its friction disk out of contact with the roller-head, and means for actuating the solenoid and the catch.

4. In a changeable exhibitor, the combination with a revolving kiosk, changeable panels carried thereby, means for changing them and for revolving the kiosk a cam and a motor carried by the kiosk and actuating said means; of an upstanding pillar fixed 60 in said support, a head carried thereby and supporting two pairs of contact rings to which the wires from a direct current and an alternating current are respectively connected through the pillar, a block carried 65 by the kiosk, two pairs of spring-pressed brushes mounted in the block and respectively contacting with the rings, and feed wires leading from the motor and respectively connected with said brushes.

In testimony whereof I affix my signature.
GEORGE W. WILLIAMSON.
